US0D1017915S

(12) **United States Design Patent** (10) **Patent No.:** **US D1,017,915 S**
(45) **Date of Patent:** **** Mar. 12, 2024**

(54) **BULK PET FOOD DISPENSER**

(71) Applicant: **Canidae, LLC**, Stamford, CT (US)
(72) Inventor: **Peter Margetis**, Louisville, KY (US)
(73) Assignee: **CANIDAE, LLC**, Stamford, CT (US)
(**) Term: **15 Years**
(21) Appl. No.: **29/813,613**

(22) Filed: **Oct. 29, 2021**

(51) **LOC (14) Cl.** **30-07**
(52) **U.S. Cl.**
USPC **D30/122**; D30/131

(57) **CLAIM**

The ornamental design for a bulk pet food dispenser, as
shown in FIGS. 1-9.

DESCRIPTION

FIG. 1 is a front left perspective view of the bulk pet food
dispenser;

FIG. 2 is a front right perspective view thereof;

FIG. 3 is a front view thereof;

FIG. 4 is a back view thereof;

FIG. 5 is a right side view thereof;

FIG. 6 is a left side view thereof;

FIG. 7 is a bottom view thereof;

FIG. 8 is a top view thereof;

FIG. 9 is a back right perspective view thereof;

FIG. 10 is a front left perspective view of an alternative
embodiment of the bulk pet food dispenser; and,

FIG. 11 is a front view of the alternative embodiment of the
bulk pet food dispenser.

1 Claim, 11 Drawing Sheets
